SEWING MECHANISM

Clarence J. Davies, Detroit, Mich., assignor to
 National Automotive Fibres, Inc., Detroit,
 Mich., a corporation of Delaware

Application June 17, 1940, Serial No. 341,048

20 Claims. (Cl. 112—198)

The present invention relates to a sewing machine and more particularly to a novel multiple head sewing machine adapted to perform a particular type of sewing, in which the various heads are laterally adjustable and may be operated out of synchronism with each other.

The present sewing machine is an improvement over the sewing machine disclosed in the copending application of Mitchell, Ratley and Davies, Serial No. 290,686, entitled "Sewing mechanism," filed August 17, 1939. More particularly the improvement in the present machine resides in part in the provision of a novel loop-forming mechanism for cooperation with a hooked sewing needle. In the copending application referred to an oscillating loop-forming member is disclosed, as a result of which all of the sewing heads must be operated in synchronism. Obviously, a plurality of heads operated in synchronism greatly increases the vibration and represents an undesirable operating condition.

According to the present invention the loop-forming mechanism comprises essentially a rotating member. The various loop-forming mechanisms are adapted to be driven from a single rotating shaft by adjustable driving connections, whereby the rotating loop-forming members may be timed out of synchronism.

Cooperating with the loop-forming mechanism is a hooked sewing needle and an oscillatable, thread-carrying looper. The hooked sewing needle and the thread-carrying looper are adapted to be driven from a single drive shaft, and the driving connection intermediate the needle and looper and the shaft are adjustable so that each set may be timed as desired. As a result, the sewing needles and thread-carrying loopers and the loop-forming mechanism of each head may be operated in exactly timed relation, and the operation of the different sewing heads may be deliberately timed out of synchronism.

Briefly described, the sewing operation performed by the instant mechanism is as follows: The loop-forming mechanism comprises a cam having a body provided with a spirally formed portion terminating in an arcuate free arm spaced from the body of the cam so as to provide an open-ended slot. The sewing thread feeds through a thread guide located adjacent the cam and radially inward from the said open-ended slot. Rotation of the cam in a direction away from the free end of the arcuate arm moves the thread laterally across the open-ended slot.

The hooked sewing needle is reciprocated in

timed relation to rotation of the cam and is moved into the open-ended slot adjacent the thread which has been positioned across the slot. Adjacent the free end of the arcuate arm I provide means which insure that the thread will be carried into engagement with the hooked sewing needle, so that as the hooked sewing needle is withdrawn it engages the thread and draws a loop of the thread through the fabric. As the needle is withdrawn through the fabric the free end of the arcuate arm disengages the loop and at the same time a new loop is formed, as above described.

The loop thus drawn upwardly through the fabric being sewed by the hooked sewing needle is impaled by a thread-carrying looper which is oscillated forwardly directly beneath the upwardly withdrawn hooked sewing needle. The looper has an eye through which is threaded the looper thread. While the hooked sewing needle is in its upward position the looper is moved laterally out of the path of descent of the hooked sewing needle, in position so that the hooked sewing needle as it descends engages a loop of the looper thread in back of the eye. The hooked sewing needle continues on to penetrate the fabric being sewed and to pick up another loop of the sewing thread, and the operation continues in this manner.

With the foregoing general remarks in mind, it is an object of the present invention to provide a rotary loop-forming mechanism adapted to form a loop in sewing thread in position to be picked up by a hooked sewing needle.

It is a further object of the invention to provide loop-forming mechanism comprising a rotary body having a spirally formed cam portion terminating in an arcuate free arm spaced radially from the body of the cam.

It is a further object of the invention to provide loop-forming mechanism comprising a cam shaft, a rotary loop-forming cam thereon having a spirally formed portion terminating in an arcuate arm, in combination with a thread-retaining member adapted to substantially abut both the cam shaft and the underside of the cam, said thread-retaining member having communicating grooves in the side and top adapted to receive a sewing thread, and to be closed in operative position by a substantial engagement with the cam shaft and the cam.

It is a further object of the invention to provide a sewing mechanism comprising a plurality of pairs of needles, and a rotary loop-forming member cooperating with each pair of needles.

and drive means for said needles and loop-forming member which may be independently adjusted so that each pair of needles and the loop-forming member operate in timed relation, and the separate sewing mechanism may operate out of synchronism.

Other objects of the invention will be apparent as the description proceeds, and when taken in conjunction with the accompanying drawings wherein:

Figure 1 is a broken and fragmentary elevation of my machine, illustrating thereon two of the plurality of sewing mechanisms;

Figure 2 is an end view of the apparatus shown in Figure 1 with parts omitted for clearness;

Figure 3 is a section taken on the line 3—3, Figure 1, in which some of the parts omitted for clearness in Figure 1 are present;

Figure 4 is a broken top plan view of the mechanism shown in Figure 3;

Figure 14 is a fragmentary section on the line 14—14, Figure 12;

Figure 15 is a schematic front elevation, partly in section, illustrating the sewing mechanism in initial position; Figure 16 is a schematic side elevation, partly in section, of the mechanism shown in Figure 15; and Figure 17 is a diagrammatic showing of the loop-forming mechanism in the position occupied in Figure 15;

Figure 18 is a view similar to Figure 15, showing the parts advanced during the sewing operation; Figure 19 is a view similar to Figure 16 with the mechanism in the position illustrated in Figure 18; Figure 20 is a view similar to Figure 17 with parts in the position shown in Figure 18; and Figure 21 is a detail fragmentary section on the line 21—21, Figure 19;

Figure 22 is a view similar to Figure 15 with the parts further advanced during the sewing operation; Figure 23 is a view similar to Figure 16 with the parts in the position shown in Figure 22; and Figure 24 is a view similar to Figure 17 with parts in the position shown in Figure 22;

Figure 25 is a view similar to Figure 15 with the parts still further advanced during the sewing operation; Figure 26 is a view similar to Figure 16 with the parts in the position shown in Figure 25; and Figure 27 is a view similar to Figure 17 with parts in the position shown in Figure 25;

Figure 28 is a view similar to Figure 15 with the parts still further advanced in the sewing operation; Figure 29 is a view similar to Figure 16 with the parts in the position shown in Figure 28; and Figure 30 is a view similar to Figure 17 with the parts in the position illustrated in Figure 28.

Referring particularly to Figures 1 and 2, the sewing mechanism comprises a frame including end members 10, only one of which is shown in

Figure 1. Spanning the end members 10 is a drive shaft 11 which is driven from any suitable source of power. The shaft 11 has keyed or otherwise secured thereto, adjacent one end, 5 a pinion 12 which is adapted to mesh with a gear 13 carried by a short shaft 14, to which in turn is secured a sprocket 15. As best illustrated in Figure 2, the shaft 14 is journaled to brackets 16, bolted or otherwise secured as indicated at 10 17 to the end members 10.

Adjacent the lower portion of the end members 10 I provide a second transversely extending shaft 21, which has keyed or otherwise secured thereto a sprocket 22 aligned with the 15 sprocket 15 previously referred to. The sprockets 15 and 22 are adapted to be interconnected and thus driven in accurately timed relation by means of a chain 23. Adjustably secured to the end piece 10, as by the elongated slots 24, is a 20 bracket 25 carrying an idle sprocket 26 which engages the chain 23 and serves to tighten the same.

The shaft 14 previously referred to has also keyed or otherwise secured thereto a second sprocket 30, which serves to drive an intermediate shaft 31 journaled in a bracket 32 secured to end members 10. For this purpose the shaft 31 has keyed or otherwise secured thereto a sprocket 33 aligned with the sprocket 30 and adapted to be interconnected therewith by a chain 34. An idle sprocket 35 is adjustably mounted on the end member 10 and engages the chain 34 to tighten the same.

By reason of the foregoing it will be apparent that the shafts 11, 21 and 31 are all driven in accurately timed relation.

Intermediate the end members 10 and rigidly secured thereto is a cross bar 40, best illustrated in Figure 3. The cross bar 40 has a plurality of brackets 41 which are adjustable therewith in ways 42, 43, the brackets 41 having forwardly and upwardly projecting arms 44 in which the main drive shaft 11 is journaled. In like manner journaled openings are provided adjacent the lower 45 ends of the brackets 41 for the reception of the shaft 31.

The sewing heads 50, indicated generally in Figures 1 and 3, are shown in detail in Figures 7 and 8. As best seen in these figures, the shaft 50 11 has keyed or otherwise secured thereto double driving gears 51, which are longitudinally adjustable along the shaft 11 and may be secured thereto in any desired position of adjustment.

The sewing heads 50 comprise main frames 52 and removable caps 53. The cap 53 is formed to cooperate with the main frame 52 so as to embrace bushings 54 surrounding the shaft 11, so as to suspend the frames 52 from the shafts. The frame 52 also supports short shafts 55 and 56 having gears 57 and 58 carried thereby. The gears 57 and 58 mesh with the gears 51 and are further interconnected by a crank pin 59 projecting from the gear 57 and secured within a suitably formed recess in the gear 53. The crank pin 59 drives a connecting rod 60 which is forked to provide a pair of downwardly extending arms 61, having their lower ends connected to a cross head 62. A plunger 63 is mounted in the head for vertical reciprocation in suitable guides 64 formed in the frame. The cross head 62 carries a pair of pins 65 to which the arms 61 are trunnioned. As will be evident, rotation of the shaft 11 results in a corresponding rotation of the crank pin 59 which reciprocates the plunger 63 vertically. The plunger 63 carries at its lower

end a hooked sewing needle 66. Guide strips 67 are secured to the frame and serve as guideways for the cross head 62, as best seen in Figure 9.

As best seen in Figures 7, 8 and 10, a jack shaft 70 is journalled in the lower part of the frame, has a threaded shaft portion 71, and is equipped with a fixed spur pinion portion 72 for a purpose which will presently appear. The lower portion of the plunger 63 is provided with a series of rack teeth as indicated at 73 in Figure 8, which are adapted to mesh with the teeth of the pinion portion 72. As will be evident, vertical reciprocation of the plunger 63 results in a corresponding rotation of the jack shaft 70. A pair of driving bell crank members 75 are pivoted on the shaft 70 and have their upwardly extending arms forked as indicated at 76 to make a slot and block connection with the connecting rod 69, blocks 77 being secured to the connecting rod 69 as best seen in Figure 8. The cranks 75 have forwardly extending arms 78 which are connected by means of cross shaft 79, best seen in Figure 10. The thread-carrying looper 80 is carried by a bell crank 81, which in turn is mounted on the jack shaft 70 and has a threaded portion 82 in threaded engagement with the threaded shaft portion 71.

The axis of the jack shaft 70 is located at one side of the axis of reciprocation of the plunger 63, and the oscillating motion of the connecting rod 69 causes a corresponding oscillation of the bell crank 75 about the axis of the jack shaft 70. This oscillating motion of the bell crank 75 is transmitted directly to the bell crank 81 and results in a corresponding oscillation of the looper 80 about the axis of the jack shaft 70. As will be evident, this oscillation of the looper 80 takes place in accurately timed relation to the reciprocation of the hooked sewing needle 66.

Referring now more particularly to Figure 10, it will be observed that the bell crank 81 is mounted so as to permit a lateral shifting thereof in the direction of the axis of the shaft 70. Vertical reciprocation of the plunger 63 results in a corresponding rotation of the jack shaft 70, and due to the threaded connection between the jack shaft and the bell crank 81 this rotation of the jack shaft 70 results in a shifting of the bell crank 81 in the direction of the axis of the jack shaft 70, which is in timed relation to the reciprocation of the hooked sewing needle 66. The arrangement is such that the looper 80 swings forwardly directly beneath the hooked sewing needle 66, when the sewing needle is raised and is then shifted transversely a short distance out of the path of the sewing needle 66 so that the hooked sewing needle 66 may impale a loop of looper thread carried by the looper 80.

A shell 85 cooperates with the frame 62 to enclose most of the driving mechanism.

As best seen in Figures 3, 4, 5 and 6, a pair of presser feet 86 are normally urged down to compress the advancing material by means of a compression spring 87 provided on plunger 82. The plungers are slidably mounted in the supporting bracket 41 previously referred to. A simple hand operated cam device 88 is provided at the top of the plunger 82 to raise the presser foot while the material is being placed in sewing position. As shown in Figure 4, this device has a pair of downwardly extending cam arms 84, eccentrically journalled in the ends of the plunger 82 by means of a pin 95.

In order to avoid breakage of the sewing needles when operating on heavy material such as

cardboard, means are provided to oscillate the sewing heads 50 through a short arc about the supporting and driving shaft 11. As previously stated the sewing heads 50 are suspended from the shaft 11. The mechanism for oscillating the sewing heads 50, as above stated, includes the drive shaft 31 and a connecting link 96, best seen in Figures 3 and 6. The shaft 31 has an eccentric cam 97 keyed or otherwise secured thereto and the link 96 embraces the cam. At its opposite end the link 96 is pivotally connected to the sewing head 50 adjacent the lower end thereof. The connection between the link 96 and the sewing head 50 is releasable and includes a transversely shiftable locking bolt 98 journalled in the lower portion of the frame 52. The bolt 98 is provided with a handle 99 so that it may be shifted laterally against a spring latch 100 to permit the sewing head 50 to be swung forwardly to facilitate threading the looper 80. As previously described, the shaft 31 is driven in timed relation to the shaft 11, and the eccentric cams 97 are positioned so that the sewing heads 50 will be swung forwardly with the work while the sewing needles are projected through the work and will be returned to their starting position while the needles are retracted.

In order to steady the sewing heads and prevent side sway and vibration, the brackets 41 are provided with forwardly extending guide bars 105 which are received between rearwardly extending guide arms 106 carried by the sewing head frames 52, as best seen in Figure 5.

Referring now more particularly to Figures 3 and 11 to 14, I have illustrated the loop-forming mechanism which is located below the bed of the sewing machine. This loop-forming mechanism comprises essentially a rotary cam 110 mounted on a vertical shaft 111 which has associated therewith a thread-retaining member 112. The shaft 111 which is rotated in timed relation with the shafts 11 and 31 is provided with a worm gear 113 which is keyed or otherwise secured thereto and which may be moved axially of said shaft in order to position the loop-forming mechanism in proper relation to its cooperating sewing needle. The loop-forming mechanism includes an adjustable housing portion 114 which is longitudinally adjustable along the frame of the sewing mechanism, suitable ways being indicated at 115. The housing portion 114 includes removable caps 116 and 117 and has mounted therein the cam shaft 111 previously referred to. Suitable bearings 118 are provided and a gear 119 is keyed or otherwise secured to the cam shaft 111 in driven relation to the worm gear 113.

The thread-retaining member 112 is longitudinally slidable in a passage 120 and is adapted to be latched in position by a spring pressed ball indicated generally at 121. As best seen in Figures 11, 12 and 13, the member 112 is adapted to substantially abut one side of the cam shaft 111, and also to substantially abut the lower surface of the cam 110. A passage for thread is provided between the thread-retaining member 112 and the cam shaft and the cam as indicated at 122.

Mounted on the housing 114 is a thread guide 123 having an eye 124 therein, and as best seen in Figure 3 the sewing thread 125 is advanced through a conventional tensioning device 126 through the eye of the thread guide 123 and through the passage 122.

A bedplate 130 is secured to the top of the housing 114 and is provided with a throat open-

ing 131 through which the hooked sewing needle 66 is reciprocable.

The cam 110 is illustrated in Figure 17 and comprises a body 135 having a generally spirally formed cam portion 136 terminating in an arcuately extending free arm 137, spaced radially from the body of the cam so as to provide an open-ended slot 138 for a purpose which will presently appear. Adjacent the free end of the arm 137 I provide a notch 139 which is adapted to insure that the sewing thread 125 is carried into engagement with the sewing needle 66. As seen in Figure 13 at 137', the arm 137 may have an upwardly tapered end so that the loop may be drawn upward to some extent before the arm 15 is completely disengaged therefrom.

In Figures 15 to 30 I have illustrated the cooperating parts of the sewing mechanism in sequential position so that the sewing operation may be fully understood. As seen in Figures 15 to 17 the 20 sewing needle 66 has drawn a loop 143 of the sewing thread 125 upwardly through the fabric F and is now starting its downward movement. The looper 80 is moving forwardly directly beneath the sewing needle 66 in position to impale 25 the drawn loop 143. The sewing needle 66 in its downward movement will pass closely adjacent the looper 80 so as to pick up a loop of the looper thread, as will subsequently appear. At the same time, the cam 110 is rotating in the direction shown by the arrow in Figure 17, and the sewing thread 125 is being moved radially outward by the spirally formed cam portion 136.

As seen in Figures 18 to 21, the sewing needle 66 has now moved downwardly and impaled a loop 142 of the looper thread 140. The looper 80 has moved forwardly and has impaled the loop 143 of the sewing thread 125. Downward movement of the sewing needle 66 has withdrawn the loop 143 of the sewing thread from the hook in the sewing needle. The cam 110 has continued its rotation and the sewing thread 125, as seen in Figure 20, has now been moved across the slot 138, the sewing needle 66 is about to enter the slot 138 adjacent its closed end and at the back of the sewing thread 125.

Referring now to Figures 22 to 24 the sewing needle 66 has substantially reached its lower position and has entered the slot in back of the sewing thread 125. The looper 80 is moving rearwardly, as indicated by the arrow in Figure 23, and is forming a loop 142 of the looper thread about the sewing needle 66.

In Figures 25 to 27 I have illustrated the next step in the operation. The sewing needle 66 is moving upwardly; the looper 80 continues its rearward oscillation; the cam 110 has continued its rotation; and sewing thread 125 has been engaged by the notch 139 which positively carries the loop of the sewing thread that was formed across the slot 138 into engagement with the sewing needle 66 above its hook. Continued upward motion of the sewing needle 66 draws a loop of sewing thread upwardly through the material being sewed.

The following step in the operation is indicated in Figures 28 to 30 in which the cam 110 is illustrated as having rotated to a position such that the free end of the arm 137 has withdrawn itself from the next loop 144 of the sewing thread. Upward movement of the sewing needle 66, as indicated in Figures 28 and 29, draws the loop 144 upwardly in position to be impaled by the looper 80 in its next forward oscillation, precisely

in the same manner as the preceding loop 143 shown in Figures 15 to 17.

The timing of the cam 110 may be adjusted in any convenient manner, as for example by adjusting the same relative to the shaft 111. Preferably, however, the cam 110 is timed by means of the following instructions: As best seen in Figure 12, rotation is imparted to the shaft 111 from the shaft 21 through gears 113 and 119. The gear 119 is loosely mounted on the shaft 111 and is adapted to be clamped in driving relation thereto by the following mechanism: The shaft 111 is provided with a shoulder 111a. The ball bearings 118 have inner races 118a, and between these races and the gear 119 are provided spacers 111b. The lower end of the shaft 111 has a clamping nut 111c provided thereon which is accessible upon removal of the removable cap 116. When the cap 116 is removed and the clamping nut 111c is loosened, the shaft 111 and the cam 110 may be adjusted relative to the gear 119, which is to be retained against rotation by reason of its meshing engagement with the worm gear 113. When the proper timing relationship has been established, clamping nut 111c is tightened and the cap 116 is replaced. At the same time the timing of the operation of each individual sewing head relative to the drive shaft 11 may be adjusted by adjusting the gears 51 and 57, 58 relative to each other. This last adjustment of course simultaneously adjusts the timing of both the sewing needle and looper since these are both driven from the crank 59. It is therefore possible to adjust the various sewing mechanisms of the machine out of phase with each other, and at the same time to insure that the various elements of each complete sewing mechanism will operate in properly timed relation. This is a very desirable result and renders the machine more efficient than the machine disclosed in the prior copending application previously referred to. In addition the loop-forming mechanism including the cam 110 operates efficiently and without the necessity of reversing the motion of any moving parts. Also, the operation of the machine is rendered more certain by reason of the provision of means for positively moving the loop drawn by the cam into engagement with the hooked sewing needle so as to be engaged by the hook formed therein.

Attention is directed to the fact that the open side of the hook on the sewing needle 66 faces in the direction of advance of the fabric F. This is very desirable in a sewing machine for sewing loose fabrics, as otherwise the hook would tend to catch in loose threads in the fabric being sewed. The loop forming mechanism is arranged to present the thread to the hooked side of the needle, as clearly illustrated in the figures.

While I have illustrated and described a single embodiment of my invention, it will be understood that this has been done merely to enable those skilled in the art to practice the invention, the scope of which is indicated by the appended claims.

What I claim as my invention is:

1. In a sewing machine having a reciprocating hooked sewing needle adapted to penetrate a fabric, pick up a loop of thread, and draw said loop through said fabric; loop-forming means cooperating with said needle and comprising a rotary shaft, a forming cam on said shaft, a thread guide member substantially engaging both said shaft and said cam, said member having a con-

tinuous groove cooperating with said shaft and cam to form therewith a thread guide passage, said cam having a spirally formed portion terminating in an arm spaced from the body of said cam, a shallow notch adjacent the free end of said arm, and means for imparting continuous, unidirectional rotation to said forming cam.

2. In a sewing machine having a reciprocating hooked sewing needle adapted to penetrate a fabric, pick up a loop of thread, and draw said loop through said fabric: loop-forming means cooperating with said needle and comprising a rotary shaft, a forming cam on said shaft, a thread guide member substantially engaging both said shaft and said cam, said member having a continuous groove cooperating with said shaft and cam to form therewith a thread guide passage, said cam having a spirally formed portion terminating in an arm spaced from the body of said cam, and means for imparting continuous, unidirectional rotation to said forming cam.

3. In a sewing machine, in combination: a hooked sewing needle; means for reciprocating said needle longitudinally through a fabric being sewed; loop-forming means comprising a cam having a spirally formed portion terminating in an arcuate arm, means for continuously rotating said cam about an axis substantially parallel to the axis of reciprocation of said needle in timed relation thereto, and a fixed thread guide adjacent the axis of said cam, whereby rotation of said cam forms a loop in said thread outwardly from the axis of said cam in position to be engaged by said needle, and thereafter releases said thread, and a shallow notch adjacent the free end of said arm for moving the thread into engagement with said needle.

4. A sewing machine comprising a plurality of hooked sewing needles reciprocable through a fabric to sew a plurality of parallel seams therein; drive means for said sewing needles comprising a first drive shaft, and eccentric means operable thereby for reciprocating said needles, said eccentric means being adjustable relative to said shaft whereby said needles may be driven out of synchronism; a thread-carrying looper cooperating with each of said sewing needles and movable forwardly beneath said sewing needles to impale a loop drawn thereby through said fabric; drive means for said loopers including said eccentric means whereby each looper is operated in timed relation to its corresponding sewing needle; loop-forming means on the opposite side of said fabric from said sewing needles and loopers, said forming means comprising rotary members adapted to form loops in thread in position to be picked up by said hooked sewing means and to thereafter release said thread whereby said sewing needle may draw a loop thereof through said fabric; and drive means for said rotary members, said drive means comprising a second shaft, means driving said shafts in timed relation, and adjustable driving connections between said second shaft and each of said rotary members, whereby said rotary members may be set independently to rotate in timed relation with their corresponding sewing needles.

5. A sewing machine comprising a plurality of hooked sewing needles reciprocable through a fabric to sew a plurality of parallel seams therein; drive means for said sewing needles comprising a first drive shaft, and eccentric means operable thereby for reciprocating said needles, said eccentric means being adjustable relative to said

shaft whereby said needles may be driven out of synchronism; a thread-carrying looper cooperating with each of said sewing needles and movable forwardly beneath said sewing needles to impale a loop drawn thereby through said fabric; drive means for said loopers including said eccentric means whereby each looper is operated in timed relation to its corresponding sewing needle; loop-forming means for each sewing needle on the opposite side of said fabric from said sewing needles and loopers, said forming means comprising a fixed thread guide, a rotary cam having a spirally formed portion terminating in a free arm adapted to draw thread through said guide, to position said thread transversely of the path of said hooked sewing needle to be engaged thereby, and finally to release said thread; and drive means for said rotary cams, said drive means comprising a second shaft, means for driving both of said shafts in timed relation, and adjustable driving connections between said second shaft and each of said rotary cams, whereby said rotary cams may be set independently to rotate in timed relation with their corresponding sewing needles.

6. In a sewing machine, loop forming mechanism for cooperation with a hooked sewing needle comprising a vertical cam shaft, a rotary cam carried thereby having a spirally formed portion terminating in a generally arcuate finger spaced radially from the body of said cam to provide an open-ended slot, and a thread-retaining member adapted to substantially abut said shaft and the underside of said cam, said member having communicating thread-receiving grooves at the side and top adapted to be closed by the said shaft and said cam respectively.

7. In a sewing machine, loop forming mechanism for cooperation with a hooked sewing needle comprising a vertical cam shaft, a rotary cam carried thereby having a spirally formed portion terminating in a generally arcuate finger spaced radially from the body of said cam to provide an open-ended slot, and a thread-retaining member adapted to substantially abut said shaft and the underside of said cam, said member having communicating thread-receiving grooves at the side and top adapted to be closed by the said shaft and said cam respectively, said member being slidably mounted with respect to said cam shaft to provide for exposure of said grooves to permit threading.

8. In a sewing machine, loop forming mechanism for cooperation with a hooked sewing needle comprising a vertical cam shaft, a rotary cam carried thereby having a spirally formed portion terminating in a generally arcuate finger spaced radially from the body of said cam to provide an open-ended slot, and a thread retaining member adapted to substantially abut said shaft and the underside of said cam, said member having communicating thread-receiving grooves at the side and top adapted to be closed by the said shaft and said cam respectively, said member being slidably mounted with respect to said cam shaft to provide for exposure of said grooves to permit threading, and latch means adapted to retain said member in operating position.

9. A multiple head sewing machine comprising a pair of drive shafts; means for rotating said shafts in timed relation; a plurality of sets of sewing elements, each set comprising a hooked sewing needle and an oscillatable thread-carrying looper; separate drive means intermediate

one of said shafts and each of said sets of elements, said drive means being adjustable whereby said sets of elements may be operated out of synchronism; a loop forming mechanism for each set of elements, and adjustable drive means connecting each of said loop forming mechanisms with said other drive shaft, whereby said loop forming mechanisms may be operated out of synchronism with each other and in timed relation to their corresponding sets of elements.

10 10. A multiple head sewing machine comprising a pair of drive shafts; means for rotating said shafts in timed relation; a plurality of sets of sewing elements, each set comprising a hooked sewing needle and an oscillatable thread-carrying looper; separate drive means intermediate one of said shafts and each of said sets of elements, said drive means being adjustable whereby said sets of elements may be operated out of synchronism; a loop forming mechanism including a rotary member for each set of elements, and adjustable drive means connecting each of said loop forming mechanisms with said other drive shaft for continuous, unidirectional rotation thereby, whereby said loop forming mechanisms may be operated out of synchronism with each other and in timed relation to their corresponding sets of elements.

15 11. A multiple head sewing machine comprising a pair of drive shafts; means for rotating said shafts in timed relation; a plurality of sets of sewing elements, each set comprising a hooked sewing needle and an oscillatable thread-carrying looper; separate drive means intermediate one of said shafts and each of said sets of elements, said drive means being adjustable whereby said sets of elements may be operated out of synchronism; a loop forming mechanism including a rotary cam having a spirally formed portion terminating in an arcuate arm for each set of elements, and adjustable drive means connecting each of said loop forming mechanisms with said other drive shaft, whereby said loop forming mechanisms may be operated out of synchronism with each other and in timed relation to their corresponding sets of elements.

20 12. In a sewing machine, a hooked sewing needle, means for reciprocating said needle, a loop-forming cam, means for rotating said cam in timed relation to said needle, said cam comprising a body having a spirally formed portion terminating in a free, arcuate arm spaced radially from said body to define therewith an open-ended slot, a thread guide located adjacent said cam and radially inward from said slot, whereby rotation of said cam draws thread from said thread guide across said slot, said needle being movable into said slot so as to hook said thread and draw the same into a loop as said free arm is withdrawn therefrom.

25 13. In a sewing machine having a horizontal bed plate upon which a fabric may be advanced; a rotary cam beneath and substantially parallel to the bed plate, and means adjacent the underside of the cam through which thread may be drawn upwardly toward the fabric on the bed plate, the cam having an arcuate slot adapted to receive a hooked portion of a vertically reciprocating needle and provided upon the outer side of the slot throughout its length with an arcuately extending arm portion, said slot being closed at one end and open at the other whereby the arm portion has a free end, said arm portion being operable during rotation of the cam to move the upwardly drawn thread lat-

erally outwardly relative to the means aforesaid so that such thread will extend on the underside and transversely across the slot and arm portion, said arm portion having means for positioning the transversely extending thread into operative engagement with the hooked portion of the needle in the slot so that the needle upon its upward stroke may pull a loop of said thread upwardly through both said slot and the fabric on the bed plate.

30 14. In a sewing machine having a horizontal bed plate upon which a fabric may be advanced; a rotary cam beneath and substantially parallel to the bed plate, and means adjacent the underside of the cam by which thread may be directed upwardly toward the fabric on the bed plate, the cam having an arcuate slot adapted to receive a hooked portion of a vertically reciprocating needle and provided upon the outer side of the slot with an arcuately extending arm portion, said slot being closed at one end and open at the other whereby the arm portion has a free end, said arm portion being operable during rotation of the cam to move the upwardly directed thread laterally outward relative to the means aforesaid so that such thread will extend on the underside and transversely across the slot and arm portion, said arm portion having a notch for positioning the transversely extending thread into operative engagement with the hooked portion of the needle in the slot so that the needle upon its upward stroke may pull a loop of said thread upwardly through both said slot and the fabric on the bed plate.

35 15. In a sewing machine having a bed plate upon which a fabric may be advanced; a rotary cam beneath the bed plate, and means adjacent the axis of the cam providing a fixed passage through which thread may be drawn upwardly toward the fabric on the bed plate, the cam having an arcuate slot adapted to receive a hooked portion of a vertically reciprocating needle and provided upon the outer side of the slot with an arcuately extending arm portion, said slot being closed at one end and open at the other whereby the arm portion has a free end, said arm portion being operable during rotation of the cam to move the upwardly drawn thread laterally outward relative to the means aforesaid so that such thread will extend on the underside and transversely across the slot and arm portion, said arm portion being provided in spaced relation to its free end with means for positioning the transversely extending thread into operative engagement with the hooked portion of the needle in the slot so that the needle upon its upward stroke may pull a loop of said thread upwardly through both said slot and the fabric on the bed plate.

40 16. In a sewing machine having a horizontal bed plate upon which a fabric may be advanced; a rotary cam beneath and substantially parallel to the bed plate, and means adjacent the underside of the cam through which thread may be drawn upwardly toward the fabric on the bed plate, the cam having an arcuate slot adapted to receive a hooked portion of a vertically reciprocating needle and provided upon the outer side of the slot throughout its length with an arcuately extending arm portion, said slot being closed at one end and open at the other whereby the arm portion has a free end, said arm portion being operable during rotation of the cam to move the upwardly drawn thread laterally outwardly relative to the means aforesaid

said so that such thread will extend on the underside and transversely across the slot and arm portion, said arm portion having means for positioning the transversely extending thread into operative engagement with the hooked portion of the needle in the slot so that the needle upon its upward stroke may pull a loop of said thread upwardly through both said slot and the fabric on the bed plate, the free end of the arm portion being upwardly tapered from the underside to the upper side thereof so that the transversely extending thread on the underside of said arm portion may follow the loop as it is drawn upwardly by the needle before the arm portion is disengaged from said thread by the rotating cam.

17. In a sewing machine having a bed plate upon which a fabric may be advanced; a rotary cam beneath the bed plate, and means adjacent the axis of the cam providing a fixed passage through which thread may be drawn upwardly toward the fabric on the bed plate, the cam having an arcuate slot adapted to receive a hooked portion of a vertically reciprocating needle and provided upon the outer side of the slot with an arcuately extending arm portion, said slot being closed at one end and open at the other whereby the arm portion has a free end, said arm portion being operable during rotation of the cam to move the upwardly drawn thread laterally outward relative to the means aforesaid so that such thread will extend on the underside and transversely across the slot and arm portion, said arm portion being provided in spaced relation to its free end with means for positioning the transversely extending thread into operative engagement with the hooked portion of the needle in the slot so that the needle upon its upward stroke may pull a loop of said thread upwardly through both said slot and the fabric on the bed plate, the arm portion being upwardly tapered at its free end to permit the transversely extending thread on the underside of the arm portion to follow the loop as it is drawn upwardly by the needle before the arm portion is disengaged from said thread by the rotating cam.

18. In a sewing machine having a horizontal bed plate upon which a fabric may be advanced; a rotary cam beneath and substantially parallel to the bed plate, and means adjacent the underside of the cam by which thread may be directed upwardly toward the fabric on the bed plate, the cam having an arcuate slot adapted to receive a hooked portion of a vertically reciprocating needle and provided upon the outer side of the slot with an arcuately extending arm portion, said slot being closed at one end and open at the other whereby the arm portion has a free end, said arm portion being operable during rotation of the cam to move the upwardly directed thread laterally outward relative to the means aforesaid so that such thread will extend on the underside and transversely across the slot and

5 arm portion, said arm portion having a notch for positioning the transversely extending thread into operative engagement with the hooked portion of the needle in the slot so that the needle upon its upward stroke may pull a loop of said thread upwardly through both said slot and the fabric on the bed plate, and means for imparting continuous unidirectional rotation to said cam.

10 19. In a sewing machine having a bed plate upon which a fabric may be advanced; a rotary cam beneath the bed plate, and means adjacent the axis of the cam providing a fixed passage through which thread may be drawn upwardly toward the fabric on the bed plate, the cam having an arcuate slot adapted to receive a hooked portion of a vertically reciprocating needle and provided upon the outer side of the slot with an arcuately extending arm portion, said slot being closed at one end and open at the other whereby the arm portion has a free end, said arm portion being operable during rotation of the cam to move the upwardly drawn thread laterally outward relative to the means aforesaid so that such thread will extend on the underside and transversely across the slot and arm portion, said arm portion being provided in spaced relation to its free end with means for positioning the transversely extending thread into operative engagement with the hooked portion of the needle in the slot so that the needle upon its upward stroke may pull a loop of said thread upwardly through both said slot and the fabric on the bed plate, and drive means for imparting unidirectional rotation to said cam in timed relation to the reciprocation of said needle.

20 25 30 35 40 45 50 55 60 19. In a sewing machine having a bed plate upon which a fabric may be advanced; a rotary cam beneath the bed plate, and means adjacent the underside of the cam providing a fixed passage by which thread may be directed upwardly toward the fabric on the bed plate, the cam having an arcuate slot adapted to receive a hooked portion of a vertically reciprocating needle and provided upon the outer side of the slot throughout substantially its length with an arcuately extending arm portion, said slot being closed at one end and open at the other whereby the arm portion has a free end, said arm portion being operable during rotation of the cam to move the upwardly directed thread laterally outward relative to the means aforesaid so that such thread will extend on the underside and transversely across the slot and arm portion, said arm portion being provided in spaced relation to its free end with a notch for positioning the transversely extending thread into operative engagement with the hooked portion of the needle in the slot so that the needle upon its upward stroke may pull a loop of said thread upwardly through both said slot and the fabric on the bed plate.
